Patented Dec. 30, 1919.

Application filed April 26, 1919. Serial No. 293,026. Term of patent 14 years.

To all whom it may concern:

Be it known that I, MORRIS SPIEGEL, a citizen of the United States, residing in the city of Chicago, county of Cook, and State of Illinois, have invented a new, original, and ornamental Design for a Sheet of Wrapping-Paper, of which the following is a specification, reference being had to the accompanying drawing, forming part thereof.

The figure is a plan view of a sheet of wrapping paper showing my new design.

The design, as shown in the accompanying drawing, consists of a net-like pattern formed by diagonally arranged intersecting cords knotted at their points of intersection.

In the embodiment of the invention illustrated in the accompanying drawing, these intercepting cords are shown as superposed upon a plurality of symmetrically disposed rectangular panels.

I claim:

The design for a sheet of wrapping paper substantially as shown and described.

MORRIS SPIEGEL.
